UNITED STATES PATENT OFFICE.

SHERWOOD B. ROBERTSON, OF NEW YORK, N. Y.

DESIGN FOR A BADGE OR SIMILAR ARTICLE.

No. 38,474.

Specification for Design.

Patented March 12, 1907.

Application filed January 16, 1906, Serial No. 296,429. Term of patent 14 years.

To all whom it may concern:

Be it known that I, SHERWOOD B. ROBERTSON, a citizen of the United States, residing in the city of New York, borough of Brooklyn, county of Kings, and State of New York, have invented a new, original, and ornamental Design for a Badge or Similar Article, of which the following is a specification.

The nature of my design is fully represented in the accompanying drawing, to which reference is made and which shows in elevation a badge or similar article embodying my design.

I claim as my invention—

The ornamental design for a badge or similar article, as shown.

SHERWOOD B. ROBERTSON.
